ELECTRIC SWITCH

Application filed December 8, 1927. Serial No. 238,580.

This invention relates to a high voltage, double break electric switch of the type which includes stationary contacts electrically connected and disconnected by a blade rotatable about and movable in planes of an axis between the stationary contacts.

In such switches as are now known, it is common to utilize a rotatable post or shaft for supporting the switch blade, limit rotation of said post by fixed stops on the stationary contact supports, and move the post in the line of its axis by rotating cam means while rotation of the post is resisted by said stops. Switches so constructed have several disadvantages. The contacts and insulators must resist forces in cantilever; the contact posts or insulator stacks cannot be made practically to effectually resist such stresses, and accordingly the contacts are thrown out of alinement and high electrical resistances are produced; a severe twisting stress or torque is imposed upon the post or shaft supporting the blade; and as a relatively quick stop of the switch mechanism is required when the switch reaches closed position, extremely careful adjustment of all parts must be made, failing which, either the switch is not fully closed or the motor operating the switch blade is overloaded by working against the fixed stops and the contact posts are strained and electrical resistance increased.

The primary object of my invention is to provide a novel and improved high voltage switch which has none of said disadvantages of the known switches and which is simple and inexpensive in construction and reliable and durable in operation.

Another object is to provide such a switch wherein the contact posts and the shaft of the switch blade are subjected to stresses or strains in tension and compression only, such stresses being those which said parts are inherently most capable of withstanding.

A further object is to provide a switch of the character described embodying novel and improved features of construction whereby the forces applied to the stationary contacts and the shaft for the blade are in the direction of greatest inherent rigidity of said

parts, whereby minimum distortion from cantilever and torque strains is ensured.

Other objects are to provide such a switch wherein high contact pressures are easily produced so that the switch is especially well suited for use with high voltages; to provide a novel and improved construction having ample latitude for overthrow or momentum of the parts in either direction to prevent injury to the switch, and to ensure that the switch is fully closed which is important where auxiliary switches are used for indicating closure of the main switch, and to obtain other advantages and results as will be brought out by the following description.

Referring to the accompanying drawings, in which corresponding and like parts are designated throughout the several views by the same reference characters,

Figure 1 is a side elevation of an electric switch embodying my invention, portions being broken away and shown in section to more clearly illustrate the details of construction;

Figure 2 is a fragmentary partial section and partial side elevation of the operating mechanism for the switch, viewing the same from a point at ninety degrees (90°) to that of Figure 1;

Figure 3 is a fragmentary front elevation of a modified form of operating mechanism, and

Figure 4 is a side elevation of the construction shown in Figure 3.

Specifically describing the illustrated embodiment of the invention, the reference character A designates the base of the switch which may be of any suitable construction, for example a channel iron as illustrated. Fixedly mounted upon said base at spaced points is a pair of electrical insulators B which are secured to the base at one end by cap screws C. Upon the other ends of the insulators are mounted contact plates D with which cooperate a laminated spring conductor or switch blade E which serves to electrically connect and disconnect the contact plates D. The line wires may be connected to the plates D in any suitable manner.

The conductor E is mounted upon a supporting means which includes an insulator F and a shaft 1 fast connected to the insulator as by a pin 2. The shaft 1 is rotatably journaled on the base A between the contacts D, and is of course insulated from the conductor E by the insulator F. The bearing for the shaft 1 comprises a substantially cylindrical hollow casing 3 secured to the base at one side thereof, the shaft being rotatable in an opening in said base and projecting beyond the base, as clearly shown in Figures 1 and 2 of the drawing. The said projecting end of the shaft 15 is screw threaded as at 5 and has threaded thereon for rotation a nut 6 which is rotatable but held against longitudinal movement in bearings 7 formed in a housing 8. The periphery of the nut is in the form of 20 a worm wheel 9 with which meshes a worm 10 mounted upon a shaft 11 journaled in bearings 12 within the casing 8, and projecting beyond the casing as shown in Figure 2 of the drawings. The projecting end of the 25 shaft is adapted to be connected by a suitable shaft coupling 13 to a reversible electric motor or other suitable means for rotating the shaft 11 alternately in opposite directions. With this construction it will be observed 30 that rotation of the nut 6 alternately in opposite directions will cause linear movement of the shaft 1, insulator F and conductor E to actuate the conductor toward and away from the contact plates D. It is necessary to also 35 rotate the supporting means for the conductor E to swing the conductor in a plane at right angles to the plane of linear movement of the conductor to move the conductor toward and from the contact plates D and 40 provide a large gap when the switch is opened. To this end the hollow casing 3 is formed in opposite sides with slots 14 in which are slidable the ends of a pin 15 projecting radially laterally from the shaft 1. 45 The slots 14 include end or terminal portions 16 which are substantially in axial planes of the shaft 1, and intermediate helical portions 17 coaxial with the said shaft. Preferably the slots open through one end of the casing 50 3 to permit a pin 15 to be inserted therein. With this construction it will be observed that upon the beginning of linear movement of the shaft in either direction, the pin 15 moves through one or the other of the terminal portions 16 of the slots 17 so that the conductor E is moved in an axial plane of the shaft toward or from the conductor plates D. This makes or breaks engagement of the conductor with the conductor plates, and there- 55 upon further linear movement of the shaft 1 cooperates through the pins 15 with the helical portions 17 of the slots 14 so as to rotate the conductor E in a plane at right angles to the plane of linear movement toward or 60 from the conductor plates. Obviously the 65

terminal portions 16 of the slots 17 limit this rotative motion of the conductor E. The terminal portions 16 of the slots 14 are so related to the pin 15 when the conductor E is in normal open or closed position, that further linear movement of the shaft in either direction is permissible after the normal position of the conductor is reached. This compensates for any possible overthrow or momentum of the driving mechanism, which without such latitude of movement in the shaft 1 would be overloaded and cause undue strains throughout the operating mechanism. 75

It will be observed that the linear movement of the conductor E is positive through the positive connection of the driving shaft 11 to the shaft 1, and the rotative motion of the shaft occurs by cooperation of the pins 15 with the helical portions 17 of the slots during the linear movement of the shaft. Cantilever or torque strains on the shaft 1, insulator F and conductor E, as well as upon the contact plates D and their supporting insulators B, are reduced to a minimum; and the contact plates and their supporting insulators B are subjected only to compression strains, while the supporting means for the conductor E is subjected only to tensional strains. Also, large contact pressure between the ends of the conductor E and the contact plates D may be obtained due to the positive and strong drive for moving the shaft 1 longitudinally; and the latitude for overthrow of the shaft 1 at the ends of its linear movements ensures that the switch will be fully closed, which is a very important function where auxiliary switches are used for indicating closure of the main switch, it being necessary that such auxiliary switches do not indicate closure until the main switch is positively closed. 95

A modified form of the invention is shown in Figures 3 and 4 in which a toggle mechanism is substituted for the nut 6 and threaded portion 5 of the shaft 1. The toggle includes two pivotally connected links 18 and 19 one of which is pivoted to the base A as at 20, and the other of which is pivotally connected to a block 21 swivel-connected as at 22 to the end of the shaft 1. The toggle links are oscillated by a draw-bar 23 so as to extend and contract toggle and thereby reciprocate the shaft 1. Rotation of the shaft is accomplished by the same means as that shown in Figures 1 and 2. 105

While I have shown and described the invention as embodied in certain details of construction, it will be understood that this is primarily for the purpose of illustrating the principles of the invention and that many modifications and changes may be made in the details of construction without departing from the spirit and scope of the invention. Therefore, I do not desire to be understood as limiting myself except as required by the 115 120 125 130

following claims when construed in the light of the prior art.

Having thus described the invention, what I claim is:

- 5 1. An electric switch comprising a pair of insulated fixed contacts, a conductor to co-
10 operate therewith to electrically connect and disconnect said contacts, means between said contacts supporting said conductor and lin-
15 early movable in opposite directions to actuate said conductor into and out of engage-
20 ment with said contacts, said supporting means also being rotatable to move said con-
25 ductor toward and from said contacts in a plane at right angles to the plane of the first-
30 mentioned movement, means for actuating said conductor supporting means through said linear movements, and cam means co-
35 operating with said supporting means during said linear movement of the latter in both
40 directions to rotate said supporting means alternately in opposite directions simultane-
45 ously with said linear movement.

2. An electric switch comprising a pair of insulated fixed contacts, a conductor to coop-
50 erate therewith to electrically connect and disconnect said contacts, means between said contacts supporting said conductor and lin-
55 early movable in opposite directions to actuate said conductor into and out of engage-
60 ment with said contacts, said supporting means also being rotatable to move said con-
65 ductor toward and from said contacts in a plane at right angles to the plane of the first-
70 mentioned movement, a driving element, means positively connected to said driving element for actuating said conductor sup-
75 porting means through said linear movement, and cam means cooperating with said sup-
80 porting means during said linear movement of the latter in both directions to rotate said supporting means alternately in opposite directions simultaneously with said linear movement.

45 3. An electric switch comprising a pair of insulated fixed contacts, a conductor to coop-
50 erate therewith to electrically connect and disconnect said contacts, means between said contacts supporting said conductor and lin-
55 early movable in opposite directions to actuate said conductor into and out of engage-
60 ment with said contacts, said supporting means also being rotatable to move said con-
65 ductor toward and from said contacts in a plane at right angles to the plane of the first-
70 mentioned movement, means for actuating said conductor supporting means through said linear movements, and stationary cam
75 means engaged by said supporting means during said linear movement in both direc-
80 tions to rotate said supporting means simultaneously with said linear movement.

85 4. An electric switch comprising a pair of insulated fixed contacts, a conductor to coop-
90 erate therewith to electrically connect and disconnect said contacts, means between said contacts supporting said conductor and lin-
95 early movable in opposite directions to actuate said conductor into and out of engage-
100 ment with said contacts, said supporting means also being rotatable to move said con-
105 ductor toward and from said contacts in a plane at right angles to the plane of the first-
110 mentioned movement, means for actuating said conductor supporting means through said linear movements, and stationary cam
115 means engaged by said supporting means during said linear movement in both direc-
120 tions to rotate said supporting means simultaneously with said linear movement.

125 5. An electric switch comprising a pair of insulated fixed contacts, a conductor to coop-
130 erate therewith to electrically connect and disconnect said contacts, means between said contacts supporting said conductor and lin-
135 early movable to actuate said conductor into and out of engagement with said contacts, said supporting means also being rotatable to move said conductor toward and from said contacts in a plane at right angles to the plane of the first-
140 mentioned movement, said supporting means having a lateral projection, means for linearly moving said supporting means, and means having a helical recess co-
145 axial with said supporting means and receiving said lateral projection, whereby said sup-
150 porting means is rotated during said linear movement thereof.

6. An electric switch comprising a pair of insulated fixed contacts, a conductor to coop-
155 erate therewith to electrically connect and disconnect said contacts, means between said contacts supporting said conductor and lin-
160 early movable in opposite directions to actuate said conductor into and out of engage-
165 ment with said contacts, said supporting means also being rotatable to move said con-
170 ductor toward and from said contacts in a plane at right angles to the plane of the first-
175 mentioned movement, means for actuating said conductor supporting means through said linear movements, and cam means coop-
180 erating with said supporting means during said linear movement of the latter in both
185 directions to rotate said supporting means alternately in opposite directions, said cam
190 means being arranged to start and stop rotation of said supporting means after the beginning and before the ending of said linear movement respectively.

195 7. An electric switch comprising a pair of insulated fixed contacts, a conductor to coop-
200 erate therewith to electrically connect and disconnect said contacts, means between said contacts supporting said conductor and lin-
205 early movable to actuate said conductor into and out of engagement with said contacts, said supporting means also being rotatable to move said conductor toward and from said contacts in a plane at right angles to the plane of the first-
210 mentioned movement, said supporting means having a screw threaded portion, a nut
215 threaded on said screw threaded portion and rotatably but longitudinally fixedly mounted, means for rotating said nut to linearly move said supporting means alternately in opposite directions, and stationary cam
220 means engaged by said supporting means during the linear movement thereof in both directions to rotate said supporting means simultaneously with said linear movement.

and out of engagement with said contacts, said supporting means also being rotatable to move said conductor toward and from said contacts in a plane at right angles to the plane of the first-mentioned movement, said supporting means having a lateral projection, means for linearly moving said supporting means, and means having a recess receiving said lateral projection and having an intermediate helical portion coaxial with said supporting means and straight terminal portions in planes of the axis of rotation, whereby said supporting means is rotated during an intermediate portion of its linear movement.

8. An electric switch comprising a pair of insulated fixed contacts, a conductor to cooperate therewith to electrically connect and disconnect said contacts, means between said contacts supporting said conductor and linearly movable in opposite directions to actuate said conductor into and out of engagement with said contacts, said supporting means also being rotatable to move said conductor toward and from said contacts in a plane at right angles to the plane of the first-mentioned movement, means for linearly moving said supporting means, and means cooperating with said supporting means at an intermediate portion of its linear movement to rotate said supporting means.
